UNITED STATES PATENT OFFICE.

WILLIAM H. COLLIER AND ARTHUR J. VANCE, OF PAINESVILLE, OHIO, ASSIGNORS TO THE COE MANUFACTURING COMPANY, OF PAINESVILLE, OHIO, A CORPORATION OF OHIO.

DRIER FOR VENEER AND THE LIKE.

Application filed July 31, 1922. Serial No. 578,768.

To all whom it may concern:

Be it known that we, WILLIAM H. COLLIER and ARTHUR J. VANCE, citizens of the United States, residing at Painesville, in the 5 county of Lake and State of Ohio, have invented certain new and useful Improvements in Driers for Veneer and the like, of which the following is a specification.

This invention relates to driers for veneer 10 and other like sheet material, the drier being of the progressive type wherein material to be dried is passed from end to end through an elongated drying chamber, a conveyor being used to effect the progress 15 of the material through the drier, wherein heating and moisture providing means and regulating means therefor are embodied.

In the drying of certain classes of materials, such as veneers, the treatment must 20 be regulated in accordance with the character of the material to be dried in order to produce a perfect output and prevent losses from checking, splitting, internal stresses, case hardening and the like defects. 25 For instance, the drying characteristics of certain material make it necessary that it should first be subjected to a low temperature, next to a high temperature and finally to a low temperature again. Other materials 30 have drying characteristics requiring other heat conditions. Again some materials require the presence of considerable moisture at first in order to avoid injury.

In dryers employing internal heat and 35 roller conveyors it has been also found that it is desirable that the steam coils used to heat the interior should be accessible for removal and repair and that the sets of conveyor rolls should be so arranged as to enable such rolls to be removed for such 40 pairs to the steam coils without loss of time.

The principal objects of the present invention are to provide an improved drier 45 having novel arrangements of heating and moisture providing devices as well as a novel construction of the feed roll supports.

Such a drier will now be described with 50 reference to the accompanying drawings and the novel features will then be specifically claimed.

In the drawings:

Figures 1 and 1^a disclose a diagrammatic isometric view of the piping arrangement in such a drier.

Figure 2 is a longitudinal sectional view

taken through a portion of the middle of the drier.

Figure 3 is a section on the line 3—3 of Figure 2.

Figure 4 is a side view of a portion of 60 the heating device showing the main exhaust header for supplying moisture to the drier.

Figure 5 is a view of the header of Figure 4 at right angles to that figure. 65

Figure 6 is a side view of a second type of header, the same being the steam supply header located at each end of the drier.

Figure 7 is a view of the header of Figure 6 at right angles thereto. 70

Figure 8 is a side view of one of the intermediate supply headers.

Figure 9 is a side view of the main driving gear stand showing certain parts of the 75 gearing.

Figure 10 is an end view thereof partly in section.

In the embodiment of the invention illustrated in these drawings there is disclosed a casing having side walls 10 which are removably secured by means of bolts 11 to vertical frame members 12 mounted on beams 13. These beams are preferably supported on rollers 14 running in channels 15 and between the beams 13 and the side frame members 12 extend cross rails 16. Along the top of the drier extends a main steam supply pipe 17 from which depend headers 18. Headers 19 are arranged between the headers 18 and form exhaust 90 headers which are connected to steam traps 20, the latter being in turn connected to a condensate pipe 21. This condensate pipe is provided with a branch 22 leading to a pump 23 which is in turn connected to a header 24 forming a circulating water supply header and located at the inlet or wet 95 end of the drier. An exhaust header 25 is provided for the circulating water supply and connects with the condensate pipe 21. Valves 26 and 27 are provided in the pipe 21, and branch 22 respectively so that the condensate may either flow out of the pipe 21 as waste or may be conducted through the branch 22. Each of the headers 18 is provided with valved branches 28 and these 100 valve branches are connected by unions 29, (see Figs. 6, 7 and 8), each with one end of a flat heating coil consisting of a series of spaced tubes 30 disposed horizontally side

105

by side and having their ends connected by return bends 31. These coils are held between clamping members 32 by bolts 33 (see Fig. 2) and the ends of the clamping members 32 rest slidably and removably on the cross rails 16. In like manner each of the headers 19 is provided with branches 33 connected each by a union 34 with the exhaust end of one of the flat coils (see Figs. 4 and 5). In each branch 33 is a check valve 34' and furthermore each branch is provided with a valved nipple 35 which may be connected, if desired, to flexible tubing for the purpose of feeding exhaust steam into the drier at any desired point.

The heating coils 30 are located directly under the lower rolls, so that the latter receive heat continually from the heating coils. The heat of the rolls is then transferred directly to the veneer or other sheet material as it is conveyed through the drier to thereby assist in driving out the moisture from the veneer. Inasmuch as the veneer is cut from the perimeter of a circular log it is necessary to flatten it during the drying process to condition it for use. An important function of the rolls, therefore, is to iron out the natural tendency of the veneer to curl and to flatten it into a sheet. For this purpose it is necessary that the rolls should be constantly heated and this is provided for by the juxtaposed heating coils.

With this construction it will be observed that any one of the coils may be removed at will without disturbing the remainder of the coils, it being merely necessary to close the branch leading to that coil by shutting the valve and uncoupling the unions 29 and 34 whereupon the coil may be drawn out after the side of the casing has been removed.

In this construction a roller conveyor is provided and the conveyor is made up in units each of which consist of a pair of side bearing frames 36 having openings 37 therein spaced longitudinally of the lower part of each frame for the reception of roller bearings 38 which in turn receive the journals 39 of the lower rollers 40 forming the supporting bed for the sheets of veneer. Above each of the openings 37 is an upwardly opening slot 41 for the reception of a journal 42 of a respective upper roller 43, the upper roller forming the pressing bed. On each of the journals 39 at one end of each roller 40 is a gear 44 which meshes with a gear 45 on the respective roller 43. On the other journal of each roller 40 is a sprocket wheel 46 over which runs a chain 47 which passes at one end around an idler roller (not shown) and at its other end around a driving sprocket 48 mounted in a main driving gear frame 49 arranged vertically at one end of the driver (see Fig. 10).

65 The vertical side frame members are also

provided with openings 50 for the journals of the lower rollers and elongated openings 51 for the journals of the upper rollers so that a continuous bed of lower and upper rollers extends from one end of the driver 70 to the other, the coils for the steam and water being located beneath the respective beds. The side frame members 36 are secured to the vertical frame members 12 by bolts 52 and thus by removing these bolts 75 any of the unitary sections may be withdrawn through the side or door. Hot air ducts 53 are suitably arranged in the drier as shown in Figure 2, these ducts being in number and position such as may be required in the particular drier.

It will be noted that the upper run of the chain 47 returns above the lower run in a channel member 47' extending longitudinally from end to end of the drier.

In the frame 49 is journalled a main drive shaft 54 carrying a driving pulley 55 and operating through reducing gearing 56 to drive a train of gears 57 connected by idlers 58, the gears 57 being preferably formed integrally with the sprockets 48. In this manner all of the sprocket chains, and consequently all of the conveyors are driven at the same speed and it will be noted that by reason of the slotted arrangement of the upper journal bearings material of different thickness may be readily accommodated. Furthermore, by means of the controlling valves the distribution of the heat in the conveyor may be regulated to a nicety and by means of flexible tubing connected to the nipples 35 steam may be introduced wherever desired.

In addition to this an economic use of heat is obtained by the utilization, whenever desired, of the condensed water from the steam coils in the hot water heating coils shown in Figure 1^a, it being understood that the steam coils in this figure and in Figure 1 are diagrammatical and not intended for accurate representation.

Having thus described the invention what is claimed as new, is:—

1. In a device of the kind described, a drying chamber, steam heating coils in one end of the chamber, other coils at the other end of said chamber, and means external to the chamber to force the condensate of the first coils through the second coils.

2. In a device of the kind described, a drying chamber, steam heating coils in one end of said chamber, water circulating coils separate from the steam heating coils in the other end of said chamber, an exhaust header having the heating coils connected thereto, a steam trap to which said header leads, and a pump connected to the water circulating coils and receiving the condensate from the trap.

3. In a device of the kind described, a

- drying chamber, a series of sets of steam heating coils arranged within the chamber and spaced longitudinally thereof, a main steam supply pipe extending along the outside of the chamber, headers connected to the main steam pipe and each provided with branches connected to the separate coils of a set, a valve in each branch, and exhaust headers connected to each set of coils.
4. In a device of the kind described, a drying chamber, a series of sets of steam heating coils arranged within the chamber and spaced longitudinally thereof; a main steam supply pipe extending along the outside of the chamber, headers connected to the main steam pipe and each provided with branches connected to the separate coils of a set, a valve in each branch, exhaust headers connected to each set of coils, a steam trap at the lower end of each exhaust header, a condensate pipe into which said traps empty, a hot water coil in one end of said chamber, and a pump connected to the hot water coil and receiving water from the condensate pipe.
5. In a drier, a drying chamber, cross rails extending in spaced relation across said chamber, a heater coil consisting of a series of pipes connected at their ends by return bends to form a continuous conduit, the centers of said pipes all being in the same plane, and a frame embracing said pipes and slidably and removably resting on the cross rails.
6. In a drier, a drying chamber, cross rails extending in spaced relation across said chamber, a heater coil consisting of a series of pipes connected at their ends by return bends to form a continuous conduit, the centers of said pipes all being in the same plane, a frame embracing said pipes and slidably and removably resting on the cross rails, a steam supply header at one end of the coil, an exhaust header at the opposite end of the coil, and unions detachably connecting said headers and ends.
7. In a drier, a drying chamber, pairs of spaced cross rails arranged in vertically spaced relation one above the other in said chamber, heater coils each slidably and removably supported on a respective pair of cross rails, steam supply and exhaust headers arranged vertically at the respective ends of said coils, valved branches extending from said headers opposite the respective coils, and unions connecting said branches with the ends of the respective coils.
8. In a drier, vertical frame members ar-
- ranged in spaced pairs, the members of each pair being disposed opposite to each other on respective sides of the drier, horizontal bearing frames detachably connected to the vertical frames at opposite sides of the driers, rolls journaled in said bearing frames, said frames and rolls forming removable units, and heating coils located directly below each horizontal set of rolls to maintain the latter in a heated condition for the purpose of causing the rolls to expel the moisture and flatten the veneer as it passes between the rolls.
9. In a drier, a unitary conveyor section consisting of a pair of laterally spaced bearing frames each having a series of roll end receiving openings arranged in horizontally spaced relation, said frames also having a series of horizontally spaced roll end receiving slots arranged above the openings and having their upper ends opening through the top edge of the frames, rolls having journal ends mounted in said openings to form a sheet supporting bed, other rolls having journal ends mounted in said slots and movable vertically therein to form a sheet pressing bed, and heating coils located directly below each horizontal set of rolls to maintain the latter in a heated condition for the purpose of causing the rolls to expel the moisture and flatten the veneer as it passes between the rolls.
10. In a drier, a unitary conveyor section consisting of a pair of laterally spaced bearing frames each having a series of roll end receiving openings arranged in horizontally spaced relation, said frames also having a series of horizontally spaced roll end receiving slots arranged above the openings and having their upper ends opening through the top edge of the frames, rolls having journal ends mounted in said openings to form a sheet supporting bed, other rolls superposed upon said first-named rolls and having journal ends mounted in said slots and movable vertically therein to form a sheet pressing bed, sprockets each fixed on a journal end of a respective lower roll, and heating coils located directly below each horizontal set of rolls to maintain the latter in a heated condition for the purpose of causing the rolls to expel the moisture and flatten the veneer as it passes between the rolls.

In testimony whereof we affix our signatures.

WILLIAM H. COLLIER.
ARTHUR J. VANCE.
